[57] CLAIM

The ornamental design for a two piece chair, as shown and described.

DESCRIPTION

FIG. 1 is a perspective view of the two piece chair showing

my new design;

FIG. 2 is a front elevational view thereof;

FIG. 3 is a side elevational view thereof taken from the right side of FIG. 2;

FIG. 4 is a side elevational view thereof taken from the left side of FIG. 2;

FIG. 5 is a back elevational view thereof;

FIG. 6 is a top plan view thereof;

FIG. 7 is a bottom plan view thereof;

FIG. 8 is a top elevational view of one piece of the two piece chair of the subject invention, illustrating for clarity only the chair back portion thereof as disassembled from the seat portion of the subject chair of my new design;

FIG. 9 is a bottom plan view of the chair back portion of FIG. 8;

FIG. 10 is a front elevational view of the chair back portion as shown in FIG. 8;

FIG. 11 is a rear elevational view of the chair back portion as shown in FIG. 8;

FIG. 12 is a side elevational view of the chair back portion taken from the left side of FIG. 8;

FIG. 13 is a side elevational view of the chair back portion of my design taken from the right side of FIG. 8;

FIG. 14 is a top plan view of the seat portion of the two piece chair of my design, as disassembled for clarity from the chair back portion illustrated in FIGS. 8-13;

FIG. 15 is a front elevational view of the seat portion illustrated in FIG. 14;

FIG. 16 is a bottom plan view of the seat portion of FIG. 14;

FIG. 17 is an end elevational view of the seat portion taken from the left side of FIG. 14; and,

FIG. 18 is an end elevational view of the seat portion taken from the right side of FIG. 14.
